UNITED STATES PATENT OFFICE.

ALFRED B. BENZING, OF ST. LOUIS, MISSOURI, ASSIGNOR TO ST. LOUIS COFFIN COMPANY, OF ST. LOUIS, MISSOURI, A CORPORATION OF MISSOURI.

COFFIN.

1,134,719.

Specification of Letters Patent.

Patented Apr. 6, 1915.

Application filed October 28, 1914. Serial No. 869,082.

To all whom it may concern:

Be it known that I, ALFRED B. BENZING, a citizen of the United States, residing at the city of St. Louis, State of Missouri, have 5 invented certain new and useful Improvements in Coffins, of which the following is a specification.

The object of my invention is to provide a coffin comprising a body having an open 10 top which is closed by a cover having a substantially air tight joint therewith and having a glazed opening through which the corpse may be viewed, said cover having a lid for the opening; a second cover is provided and has an opening registering with 15 the opening in the first cover and is provided with a lid to close such opening; and with this and other objects in view my invention consists of the parts and the combination of parts as will be hereinafter 20 pointed out.

In the accompanying drawings forming part of this specification, in which like numbers of reference denote like parts wherever 25 they occur, Figure 1 is a top plan view of a coffin embodying the present invention with a portion of the outer cover broken away thereby disclosing a portion of the inner cover and associated parts; Fig. 2 is a side view of the coffin partly in plan elevation and partly in section; Fig. 3 is a sectional view transversely across the width of the head end of the coffin; Fig. 4 is a fragmentary top view, partly in plan and partly in 30 section, looking down upon the head end of the coffin, the outer cover and the lid of the inner cover having been removed, showing a form of member for strengthening the corners of the receptacle and a form of construction for slidably supporting the frame of the screen upon adjacent portions of the outer cover; Fig. 5 is a fragmentary sectional view on an enlarged scale on the line 35 6—6, Fig. 1; Fig. 6 is an end plan view in elevation showing the lid of the outer cover and the lid of the inner cover of the coffin 40 open.

A metallic coffin of this invention comprises preferably a receptacle 1, an inner 45 cover 2, and an outer cover 3, all metallic structures made of any suitable material, such, for instance, as drawn steel.

Referring now for the purpose of illustration to structures made of drawn steel 50 to construct a metallic coffin whose general

outline is the rectangular shape, best seen in Figs. 1 and 2, receptacle 1 is preferably made by drawing into the desired shape, two similarly shaped side pieces 4, two similarly shaped end pieces 5, and a bottom 60 piece 6, each of which side pieces 4 and end pieces 5 bears an inwardly turned flange 7 at its upper edge and an inwardly turned flange 8 at its lower edge, said flange 7 being adapted to overlap adjacent portions of a member 13 (hereinafter described) and flange 8 being adapted to overlap adjacent portions of bottom piece 6. Each of said side pieces and each of said end pieces 65 preferably bear a shoulder 9 provided at an appropriate distance from, and substantially parallel to said flange 7. Side pieces 4 and end pieces 5 may bear molding-shaped adornments or the like, such, for instance as the molding-shaped adornments 10 best 70 seen in Figs. 2, 3, and 6, said adornments serving, also, to stiffen or strengthen the parts bearing same, and bottom piece 6 is preferably provided near its outer edge with a groove 11 (Figs. 2 and 3), which groove 75 is adapted to serve as a hand hold or convenient grasping means for carrying and handling a coffin in its finished or unfinished state, said groove 11, as well as said 80 adornments 10, said shoulder 9, said flanges 7 and 8, and the like being preferably formed upon their respective parts in the 85 process of manufacturing said parts.

Side pieces 4, end pieces 5, and bottom 6 assembled and set up form receptacle 1, as 90 above described, and the joints of the various parts are preferably soldered or otherwise hermetically sealed, or they may be made air-tight in any other suitable manner. Strengthening members 12 may be provided 95 at the corners as shown in Fig. 4, or elsewhere on said receptacle 1, said strengthening members preferably extending from flange 7 downward to bottom 6 and following, in a general way, the contour of the adjacent portions of the inner wall or walls of 100 said receptacle 1 and being preferably soldered in place on the inside of said receptacle.

A lip-member 13, preferably approximately Z-shaped in cross-section, bearing a depending flange 14 at its inner edge extends around the mouth of receptacle 1 and is adapted to be supported by flange 7 about 105 said mouth, the upper surface of the upper 110

ledge of said member being adjacent to the under surface of flange 7 and being preferably soldered thereto to form a hermetically sealed joint therewith, or is otherwise secured thereto in an air-tight joint. The lower ledge of said member with its depending flange is adapted to form a lip about the mouth of receptacle 1, and a member 15 (preferably a flat steel bar) is borne by the under side of said lower ledge of lip-member 13 adjacent depending flange 14, said member being preferably soldered to said lip-member, the principal purpose of said member 15 being to provide thickness of material for a plurality of screw-threaded holes adapted to receive the screws 16 as hereinafter more particularly described.

Inner cover 2 is adapted to close the opening formed by the mouth of receptacle 1 and bears a flange 17 supported upon a gasket 18, which gasket 18 rests upon the upper surface of the lower ledge of member 13 and is adapted to form an air-tight joint between said upper ledge and said flange 17, said gasket being made of any material, preferably asbestos, suitable for making said joint air-tight. Flange 17 supports a member 19, preferably a flat steel bar, and is preferably constructed, as best seen in Fig. 3, by looping a portion of the material of inner cover 2 about said member intimately following the outline of said member and the end of said loop may be soldered to adjacent inner portions of said inner cover, the purpose of said member 19 being to provide a strong flange of greater thickness of material than that of the portions of the inner cover adjacent to said flange so that screws 16 inserted through appropriate holes in said flange and passing through gasket 18 may be screwed in place in screw-threaded holes in the lower ledge of member 13 and in member 15 borne by said member 13. By screwing said screws 16 home, an air-tight joint is formed by means of gasket 18 between flange 17 and the lower ledge of member 13 about the mouth of receptacle 1, and inner cover 2 is thus held firmly in place. The structure of said inner cover 2 rises from flange 17 preferably in a graceful dome-shaped curve and an opening 20 at the top of said inner cover is provided with a lid 21, and, a plate of glass 22 is provided for said opening, supported to cover same as hereinafter described. Opening 20 preferably extends from a portion of said inner cover near the head end of the coffin to a point above the waist line of a corpse resting in the receptacle of said coffin and may be of any desired width so that the features and upper portion of the body of said corpse may be conveniently viewed through said plate of glass when said corpse is lying in state as hereinafter described. The edge about the

mouth of said opening 20 bears a depending flange 23, best seen in Fig. 5, and upon the under side of said inner cover a member 24 is soldered to said under side and surrounds said depending flange 23 at a slight distance therefrom, said member being preferably made of soft lead and adapted to form a hanger or bracket for supporting said plate of glass 22, said member 24 having preferably an approximate Z-shaped form in cross-section when same is in place as best seen in Fig. 5. In order to form an air-tight joint between said plate of glass and depending flange 23 about the mouth of opening 20, the space between said flange 23 and said member 24 is filled to the full depth of said flange with cement 25 or other binding means of any composition suitable for making an air-tight joint, the inner cover, for convenience of working, preferably having been inverted and the glass supporting flange of soft lead member 24 having been bent straight or substantially perpendicular to the supporting inner surface of the inner cover 2, and said plate of glass 22 is placed upon the edge of said depending flange with the portion of said plate of glass adjacent to its edges extending over said cement and with the edge of said plate of glass abutting the side of member 24 adjacent thereto, the end portion of said member 24 extending beyond the inner surface of said plate of glass being bent in the form of a flange over upon the portion of said plate of glass adjacent to the edge of same. When cement 25 has set, the desired air-tight joint will have formed, said cement binding parts adjacent thereto in a sealed joint, the flange on member 24 bent over upon the inner surface adjacent the edge of said plate of glass being adapted to assist in supporting said plate of glass in place.

Lid 21 is preferably swung open and shut upon a device 26 (Fig. 5) or a plurality of such devices depending from a flange 27 borne by said lid, said flange being formed by bending the material of said lid around its edge inwardly, said depending member being secured to said flange by solder or by any other suitable means and said depending member 26 protruding inwardly through an appropriate opening in said inner cover, so that said lid may be swung open and shut by means of said depending member operating in said opening. Depending member 26 and the hole in inner cover 2 associated therewith are so constructed that said member may be removed from said hole and said lid bearing said member removed entirely from said lid. Pocket 28 is provided upon the inside of said cover 2, said pocket being supported at the edge of its mouth by the inner surface of said cover and joined thereto to form a

hermetically sealed joint therewith preferably by means of solder, said pocket being adapted to cover said opening and being so constructed as to house the part of depending member 26 protruding below inner cover 2.

Lid 21 may be provided with a suitably located snap-latch 29 of any well-known construction, latching through an appropriate opening in inner cover 2 upon an adjacent portion of the inner surface of said cover, said latch being provided with a lifting lever 30 extending through an appropriate opening in said lid 21 to permit said latch to be operated conveniently to disengage same from locking relation with said lid and said cover when it is desired to raise said lid.

For the purpose of symmetrical appearance in an inner cover 2 whose lid 21 is constructed, as described and as best seen in Figs. 1 and 2, to cover an opening 20 extending only partially the length of said inner cover 2, there is preferably provided a raised portion 32 extending from a portion adjacent the foot of the coffin toward the middle portion to simulate the appearance given to the lid bearing portion of said inner cover, and, also, a design in relief, such as the elliptical-shaped design 33, Figs. 1 and 2, may be provided over the middle portion of said cover. It will be understood that said designs in relief, 32, and 33, are merely ornamental and may be made integral with said cover in the process of manufacture and may be varied as to shape and design in any desired manner, or may be omitted entirely, or they may be separately made, as shown in Fig. 2, and adapted to cover openings 34 and 35 under each, respectively, in which case the joints formed by the edges of said covering designs 32 and 33, respectively, with adjacent portions of said cover 2 are hermetically sealed, preferably by means of solder, or otherwise made airtight.

Outer cover 3 is adapted to cover inner cover 2 and is provided with an inwardly turned flange 36 borne by the base of said outer cover 3, which flange is adapted to rest on the upper surface of inwardly turned flange 7 of the upper edge of receptacle 1. Flange 36 may be provided with a strengthening member 37 of any suitable material, preferably a wooden bar, said member being preferably supported by said flange by means of an extension of the material of said flange being bent around adjacent portions of said member, the end portion of said extension being bent against adjacent portions of the inner surface of said outer cover 3 and said end portion may be soldered or otherwise secured to said inner surface, or it may be merely pressed up against said inner surface. By this con-

struction member 36 is clasped in place as best seen in Fig. 3. Flange 36 resting upon flange 7 may extend slightly beyond the outer edge of flange 7, as shown in Figs. 2 and 3.

Locking devices of any suitable construction may be provided to lock said outer cover in place upon said flange 7 and said locking device may consist of sets of female members being adapted to engage in locking relation, forwardly or backwardly turned male members (not shown) depending from flange 36.

An opening 39 is provided in the top of said outer cover, the edge of said opening being preferably finished by turning a portion of the material adjacent to said opening upon itself as best seen in Fig. 3, said opening being adapted to permit lid 21 of inner cover 2 to be swung open therethrough as best seen in Fig. 6. A lid 40 is provided for said opening 39, said lid being preferably swingingly to open and close over said opening.

Lid 40 may be provided with a supporting bar 44 (Fig. 6) having one end in swiveled attachment with said lid and having a notch 45 at its free end adapted to engage a pin 46 borne by the edge of opening 39 when lid 40 has been swung to open position, shown in Fig. 6, thus holding said lid in said open position. To close lid 40, notch 45 is lifted out of engagement with pin 46, whereupon bar 44 swinging on its swiveled end will slide along pin 46 as lid 40 is dropped to closed position. If desired, a number of notches such as notch 45 may be provided adapted to engage pin 46 and support lid 40 open in other positions than the upright position shown in Fig. 6. An open lid supporting device 47 similar to that just described may, also, be provided for lid 21, as shown in dotted outline in Fig. 6. Moreover, any well-known means may be substituted for that described for supported lids 40 and 21 in any desired open position.

A pair of groove-bearing members 51 may be provided, each of said members being borne by the inside of outer cover 3 adjacent to opposite sides of opening 39 and may extend from the portion adjacent to the head end of the coffin toward the foot end as far beyond the end of opening 39 as may be convenient for the purpose hereinafter mentioned. Groove-bearing members 51 are adapted to support frame 52 of framed screen 53, each member 51 supporting an adjacent side of said frame in slidable engagement, said screen being adapted to protect plate of glass 22 from fly-specks or from being soiled by the touch of hands or the like when said screen is slid in said groove-bearing members to a position over said glass. When desired, said frame may

be slid toward the foot of the coffin away from opening 39, thus uncovering said pane of glass, said groove-bearing members 51 being extended sufficiently in the direction 5 of the foot of the coffin to permit this, as shown in Fig. 2.

For the purpose of providing an unbroken line in profile along the top of a coffin closed with outer cover 3 thereon, spacing members 54 and 55 may be provided borne by adjacent portions of lid 40 and outer cover 3, respectively, said spacing members being adapted to maintain the profile line of the top or outer cover 3 in even alinement 15 where the continuity of said line is broken by lid 40 and opening 39.

Strips of wood 56 may be provided borne in any suitable manner by appropriate parts and surfaces of the inside of the coffin, such, 20 for instance, as the inside of bottom 6 adjacent to side pieces 4 and end pieces 5, and the inside of outer cover 3, said strips being adapted to serve as convenient supporting means for attaching thereto, hanging, draping 25 or otherwise disposing thereon the cloth lining, drapery, and the like, with which it may be desired to adorn the interior of said coffin.

In screwing inner cover 2 in place upon 30 receptacle 1 by means of screws 16, it may occur that a screw 16 is omitted, or it may occur that a threaded hole in the lower ledge of member 13 and member 15 supported thereby has been imperfectly made, or a 35 screw 16 may be defective, or the like, thus allowing air to pass into the compartment formed by said inner cover and said receptacle, thus destroying the air-tight feature of said compartment. To provide against 40 this, a plate 57, preferably made of steel, may be furnished, said plate being adapted to extend around the inside of receptacle 1 preferably supported in a diagonal position in its width between shoulder 9 and the 45 angle or shoulder formed by the under surface of member 15 and the outer surface of the portion of depending flange 14 extending below said member 15. All joints or seams at the edges of said member being 50 hermetically sealed, preferably by being soldered, or being otherwise made air-tight. As shown in Fig. 3, plate 57 set in as described with air-tight joints will form an air-tight barrier against leakage of air 55 through holes for screws 16 or the like, thus insuring the air-tight feature of the compartment occupied by a corpse in the coffin embodying the present invention. Member 57 serves, also, to strengthen and brace the 60 parts with which it is associated.

The metallic coffin herein described is preferably used in the following manner: Outer cover 1 and inner cover 2 being removed from receptacle 1, the corpse is placed 65 within receptacle 1 and inner cover placed

upon said receptacle and is held firmly in place by means of screws 16 so that flange 17 at the base of said inner cover is pressed firmly upon gasket 18 on the lower ledge of member 13 to form an air-tight joint, and all 70

other joints and seams in receptacle 1 and inner cover 2 having been made air-tight in construction, the corpse resting in receptacle 1 with inner cover screwed in place thereon as above described is in an air-tight compartment. Outer cover 3 is placed in position resting with flange 36 upon flange 7 and is held locked in that position by means of a locking device, part of which locking device 75

is shown at 38 on Fig. 1. To permit the 30 corpse to be viewed as it lies in state in said air-tight compartment, it will be necessary merely to raise lid 40, and, if desired, remove same, then raise lid 21 through opening 39 of outer cover 3, screen 53 having been 35

slid beyond said opening toward the foot end of the coffin to permit said lid 21 to be raised, and, if desired, lid 21 may, also, be removed entirely from the coffin. Thus the 40 features and upper portion of the body of 90

the corpse will be in view through plate of glass 22, but may not be touched. Should it be desired temporarily to screen the view of 45 said corpse, this may be conveniently and quickly done by sliding screen 53 in place 95

over plate of glass 22 whereby said view will not only be screened but, also, plate of glass 22 will be protected from fly-specks or from being soiled by the touch of hands or otherwise. A great advantage of the coffin of 100

this invention is that there is no long and tedious delay required to close same when it is desired to remove the coffin with the 105 corpse therein from the chapel, residence, or other place where it has lain in state to be viewed by friends and relatives, the operation of closing same being quickly and simply accomplished without causing any disturbance in the following manner: Screen 110

53 having been slid out of the way toward the foot of the coffin, lid 21 of inner cover 2 is closed over opening 20 and locked with snap-latch 29, whereupon lid 40 of outer 115

cover 3 is closed over opening 39 and locked with snap-latch 43. 115

It is, of course, understood that a coffin embodying the present invention may have any desired shape.

Many changes in the details of construction and arrangement of parts may be made 120 without departing from the nature and spirit of the present invention.

I claim:

1. A coffin comprising a body having an open top, a cover adapted to close said body substantially air tight, a second cover adapted to cover the first named cover, said first named cover having a glazed opening, a lid for said opening removably hinged to the first named cover, said second cover having 125

an opening to permit the said lid to be swung open therethrough, and a lid for the opening in the second named cover.

2. A metallic coffin comprising a body portion the upper marginal edge portion of which is bent inwardly to form a flange, an approximately Z-shaped lip member secured to the flange of the body portion and extending around the mouth of the body portion, an inner cover adapted to close the mouth of the body portion, a marginal flange integral with said cover and secured to the lip member with an air tight joint, said cover also having a glazed opening, pockets depending from the under face of the inner cover open only at the top, a lid having in-
- turned marginal edge portions, hinge members secured to and depending from said edge portions and extending into the said pockets, said cover being provided with a sight opening and an outer cover having an inwardly turned marginal portion constituting a flange adapted to rest upon the flange of the body portion, and a lid carried by said outer cover over the lid of the inner cover.

In testimony whereof I hereunto affix my signature in the presence of two witnesses.
